CLAIM

The ornamental design for a Christmas tree storage bag, as shown and described.

DESCRIPTION

FIG. 1 is a top, front, right side perspective view of a Christmas tree storage bag showing my new design; FIG. 2 is a bottom, rear, left side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of portion 9 in FIG. 1; FIG. 10 is an enlarged view of portion 10 in FIG. 1; FIG. 11 is an enlarged view of portion 11 in FIG. 1; FIG. 12 is an enlarged view of portion 12 in FIG. 1; FIG. 13 is an enlarged view of portion 13 in FIG. 3; and, FIG. 14 is an enlarged view of portion 14 in FIG. 5.

The stippling shown on the Christmas tree storage bag in the figures depict contrast in appearance. The dotted lines shown on the Christmas tree storage bag depict stitching that form no part of the claimed design. The unevenly dashed broken lines define the boundary of enlarged views and form no part of the claimed design.
